(57) **CLAIM**

The ornamental design for a push-button—kitchen and bathroom tap, as shown and described.

DESCRIPTION

FIG. 1 is a top, front, right side perspective view of a push-button-kitchen and bathroom tap in accordance with our new design;

FIG. 2 is a right side elevational view thereof;

FIG. 3 is a left side elevational view thereof;

FIG. 4 is a front elevational view thereof;

FIG. 5 is rear elevational view thereof;

FIG. 6 is top plan view thereof;

FIG. 7 is a bottom plan view thereof; and,

FIG. 8 is a top, rear, left side perspective view thereof.

The broken lines represent portions of the push-button—kitchen and bathroom tap that form no part of the claimed design.
